UNITED STATES PATENT OFFICE.

CHRISTOPHER LAUTERBACH, OF BALTIMORE, MARYLAND.

AUTOMATIC AIR-ESCAPE VALVE.

1,073,354.

Specification of Letters Patent. Patented Sept. 16, 1913.

Application filed April 15, 1912. Serial No. 691,023.

To all whom it may concern:

Be it known that I, CHRISTOPHER LAUTERBACH, a citizen of the United States, residing at Baltimore city, State of Maryland, have invented certain new and useful Improvements in Automatic Air-Escape Valves, of which the following is a specification.

This invention is in the nature of an air escape valve for vapor-heating apparatus.

The object of the invention is to provide an improved automatic device of this character whereby the escape of air from, and the receipt of vapor by, all of the radiators of a system or apparatus, and temperatures in the radiators, will be automatically controlled, by the rise and fall of the temperature of the outside atmosphere. In an ordinary system the valve will be placed in the return line, at a point near the boiler.

With these and other objects in view, the invention consists in the improved construction, arrangement and combination of parts hereinafter fully described and afterward specifically claimed.

In order that the construction and operation of my invention may be readily comprehended, I will now proceed to describe the same in connection with the accompanying drawing which represents a central, vertical, sectional view of an approved embodiment of the invention, part of the structure being broken away and parts shown in elevation.

Referring specifically to the drawing, 1 indicates the bottom casting which is substantially cylindrical and hollow, the lower end being contracted in diameter and externally threaded as at 2 to fit the thread 40 of a pipe or coupling projecting from a radiator, in a well known manner. Near the upper end thereof the casting is provided with a transverse diaphragm 3 in which are ports 4, and the extreme upper end is internally threaded, as at 5, to receive the lower, externally threaded end of a hollow cylindrical shell 6, an upwardly extending lug 7 projecting centrally from the top center of the diaphragm 3, upon which lug is seated a hollow cylindrical supporting post 8. Threaded upon the upper externally threaded end of the shell 6 is the top casting 9 which is substantially cylindrical and externally threaded at upper end to receive 55 an internally threaded adjusting cap 10. This top casting is provided with a trans-

verse diaphragm 9' having a central threaded opening to receive a hollow externally threaded adjusting plug 11. The two ends of the hollow adjusting plug 11 are shaped as valve seats, the lower one to receive and co-act with the upper conical tip 12 of a hollow bell float 13 which is supported upon the upper end of the supporting post 8 and is of a diameter to leave a space 14 in the shell 6 all around said float. The upper valve seat of the adjusting plug 11 is intended, under circumstances herein-after described, to receive and co-act with the conical lower center 15 of a disk 16, the conical edge 17 of which co-acts with a valve seat 18 formed in the upper end of the top casting 9, the disk 16, adapted to seat on the plug 11 when the plug is adjusted to a sufficient height to hold the disk 16 above the valve seat 18. This disk is provided in its top center with an upwardly extending socket 19 to receive a centering screw 20 threaded through the center of the top of the adjusting cap 10. Port holes 21 extend through the top of the adjusting cap 10 around the centering screw 20. The bell float 13 and the disk 16 are constructed of brass, aluminum, or like material, aluminum being preferable on account of its lightness and anti-oxidizing qualities.

The operation of this invention in connection with a vapor-heating system, is as follows: Assuming a cold plant with a fresh fire being made and a combination vacuum and steam gage therein indicating 0 or zero. As soon as the water increases in volume from the heat of the fire, the increase of volume of water compresses the air in the apparatus if there is no outlet for air and the gage will record this pressure. With this air escape, however, this increase of pressure does not take place. At the slightest increase of volume of water, the amount of air representing that increase is discharged through the air escape by way of the ports 4, passing around the float 13, raising the disk 16 and thence through the ports 21, to the atmosphere. Upon the contraction of the medium within the system there is a partial vacuum produced in the apparatus and the water in the boiler boils at a temperature below 212 degrees. The air escaping through the air escape continues if the fire in the boiler is maintained until the entire apparatus is hot, which is done without the pressure gage pointer moving from

the 0 or zero mark, or without the water in the boiler going above 212 degrees temperature. If at this stage the fire in the boiler gets too low to maintain the temperature of the water at 212 degrees, a vacuum is formed in the apparatus and the atmospheric pressure is exerted downwardly upon the disk 16, pressing it down upon its seat and thereby preventing air from passing into the apparatus. When all the air in the apparatus has been discharged through the air escape and all the radiators and pipes are hot, and the fire is sufficiently strong to generate more vapor than the radiators and pipes will condense, steam is formed and this, when it reaches a pressure of one-half pound, passes through the ports 4 and up under the float 13, raising the float and closing the hollow plug 11, preventing any further egress and allowing the steam to be raised to any desired pressure. This is owing to the fact that the ports 4, are larger than the ports 21. This, however, happens only when the entire apparatus is hot, in the early fall and late spring, when only a low degree of heat is required in the rooms or house, to maintain the desired internal temperature, usually about 70 degrees, the air and currents in the smoke flue create a slight vacuum in the smoke pipe, just enough to draw the necessary amount of air through the cracks around the ash pit and draft doors, (these doors and the damper in the smoke pipe remaining closed as long as coal is being used as fuel), to have a fire only hot enough to generate a small amount of vapor in the boiler. This, while generating, discharges its equivalent volume of air through the air escape to the atmosphere. This small amount of vapor, on account of the general construction of the apparatus, passes to the radiator farthest away from the boiler, as well as to those nearest to it, heating all to a uniform temperature and consequently all the rooms to the same temperature. The escape of air responding to the slightest pressure in the apparatus, responds at once when the temperature of the outside air gets lower and affects the velocity of the air currents in the smoke flue, increasing the partial vacuum in the smoke pipe, and that in turn increasing the velocity and volume of air passing through the cracks of the ash pit and draft doors, thereby generating more vapor, which, being lighter in weight than the air in the apparatus, seeks a higher level, until eventually the air escape valve is affected.

The radiators may only be warm across the top, (sometimes with temperature as low as 75 to 80 degrees), or hot, or one quar-

ter, or one-half, three quarters or wholly hot, depending entirely on the amount of air discharged through the air escape. With this discharge of air through the air escape, 65 and just the necessary amount of vapor being generated in the boiler, to heat the rooms to the desired temperature, it becomes entirely unnecessary to open or close any of the radiator valves, to regulate to proper amount 70 of heat in the room or rooms.

On account of the instant response of the air escape to the slightest internal pressure, the heat responds to the variations in the outside temperatures, generating by the increase or decrease of the heat of the fire in the boiler, more or less vapor, or always sufficient vapor to maintain the desired temperatures in the rooms. There may be one, two, three or more of these air escapes located on the return lines of the vapor heating apparatus not shown in the drawings. If more than one, then those located farthest from the boiler have the lightest disk 16, and those closer to, or at the boiler, have the 85 heavier disk 16. This is done to have the radiators farthest from the boiler relieved of the air, and to have them receive the vapor at the same time that those closer to the boiler get it. 90

Having thus fully described my invention, what I claim as new, and desire to secure by Letters Patent of the United States, is:

An air escape valve providing a hollow cylindrical shell, a bottom hollow casting secured thereon, a diaphragm in said casting and provided with ports to admit air into said shell, a supporting post on said diaphragm, a hollow bell float adapted to normally rest on said post, a conical tip on the upper end of said float, a top casting secured on said shell having a valve seat in the upper end thereof, a diaphragm in said top casting, a hollow plug threaded in said diaphragm for adjustment, valve seats being formed at 105 each end of said plug, the lower valve seat adapted to co-act with the conical tip on the float, an adjusting cap secured on the upper end of said top casting, a disk between said cap and top casting, said disk having conical 110 faces one adapted to co-act with the upper valve seat of said plug, and the other to co-act with the valve seat in said top casting, and a centering screw secured in said cap adapted to adjust said disk. 115

In testimony whereof I affix my signature in presence of two witnesses.

CHRISTOPHER LAUTERBACH.
